APPARATUS FOR COATING

Clauss B. Strauch, New York, N. Y., assignor, by
mesne assignments, to F. J. Stokes Machine
Company, Philadelphia, Pa.

Application February 24, 1934, Serial No. 712,816

13 Claims. (Cl. 91—18)

This invention relates to a method and apparatus for coating the inner surfaces of collapsible tubes or the like with liquefied hot petrolatum or similar substances.

5 An object of the invention is to provide a novel system whereby a single operator in about one minute's time may coat the interior of a gross or more of tubes.

10 Another object is to provide a system for coating the tubes with a pliable adherent sealing material which will not evaporate, requires no previous treatment of the tubes, no solvents or drying, does not clog the tube outlet, protects the contents from cork and other acids, as well as 15 alkalis and costs only about one-thirtieth that of other materials.

With the foregoing objects outlined and with other objects in view which will appear as the 20 description proceeds, the invention consists in the novel features hereinafter described in detail, illustrated in the accompanying drawings and more particularly pointed out in the appended 25 claims.

Fig. 1 is a vertical sectional view of a preferred 25 form of the apparatus.

Fig. 2 is an enlarged vertical sectional view of 30 one of the tubes and showing means for coating the interior of the same through a device introduced through the top of the tube, which device plugs the lower end of the tube during the filling operation and provides for overflow of coating material.

Fig. 3 is a similar view but showing the tube 35 slightly lower relative to the filling device to permit discharge of the coating material through the lower end of the tube.

Fig. 4 is a vertical sectional view on the line 40 4—4 of Fig. 2.

Fig. 5 is a sectional view of a modification in 45 which the coating material is introduced through the bottom of the tube rather than through its upper end.

Fig. 6 is a view similar to Fig. 5 but showing 45 means to permit overflow when a bottom filling device is used.

In the drawings, 7 designates a casing having side walls 8 (only one of which is shown), a back 9, an open top 10 and an open front 11.

50 A supply tank 12 to contain hot liquefied petrolatum or the like is rigidly supported at the upper end of the casing and has a large number (144 for example) of depending spouts 13 through which the coating material is discharged. Flow 55 through these spouts is controlled by any suit-

able means such as a plate 14 which slides on the bottom of the tank and is provided with ports 15 corresponding in number to the spouts. The plate may be moved by any suitable means. For instance, the operator may manipulate the same 5 by a handle 16 that is pivotally mounted at 17 and is connected at 18 to the plate.

The spouts feed the coating material into pipes 19, corresponding in number to the spouts, and depending from a stationary shelf 20 that is supported in the casing. Each of these pipes is provided at its lower end with a stopper 21 having an inverted cone-shaped lower end 22. Near the stopper each pipe has one or more ports 23 to allow the discharge of the coating material. 15

A tray 24 has ports 25 corresponding in number to the pipes and is designed to support empty collapsible tubes 26. The tray carries a depending funnel 27 and it is designed to be raised and lowered so as to bring the tubes 26 into such position that the stoppers 21 close the lower ends of the tubes. To permit elevating and lowering of the tray and funnel, they may be suspended on ropes 28 which pass over pulleys 29 that are rotatable on axles 30 rigidly supported by the 25 casing. Weights 31 carried by the ropes will function to raise the tray and to hold the same in elevated position. In this form of the invention each pipe 19 is provided with an overflow 30 conduit 32 that communicates with a passageway 33 extending through the plug 21, whereby during the filling operation excess coating material will overflow into the funnel 27 and will thereby be prevented from flowing over the upper edge of the tube 26 with which the stopper is associated. 35

Hot material discharged from the tubes passes from the funnel 27 into a sump 34 and is fed from the same by a pump 35, through a filter 36 and a pipe 37 back into the supply tank 12.

As petrolatum congeals at normal temperatures, means are provided to maintain the same in fluid condition. This may take the form of a plurality of burners 38 and 39 arranged at the lower end of the casing for heating the sump and pump. Gases from these burners will flow upwardly as indicated by the arrows and some of them will be directed by a baffle 40 toward the tubes 26 and pipes 19. 40

In operation, let us assume that a gross of the tubes 26 is arranged in the original box. If the 50 bottom of the box is cut off and the tubes are placed on the elevator 27 while the latter is in lowered position, the spouts 13 of the tubes will enter the apertures 25 of the plate 24. Then the operator can raise the elevator to cause the plugs 55

or stoppers 21 to close the lower ends of the tubes and the weights 31 will hold the elevator in raised position. Now the handle 16 can be manipulated to feed the fluid petrolatum through 5 15, 13, 19 and 23 into the tubes 26. Should the operator release too much coating material from the tank 12, the excess amount will overflow through 32 and 33. When the tubes have been filled to the desired height, the valve plate 14 is 10 moved to closed position and then the elevator is lowered so that the coating material is discharged through the spouts of the tubes into the funnel 27 as indicated in Figs. 1 and 3.

After the tubes have been emptied, of course, 15 the operation may be repeated.

In the modification illustrated in Figs. 5 and 6, the tubes are filled from below and this may be accomplished by extending the pipes 19a through 20 the elevator plate 26a so that the plate may slide up and down on the pipes. Each pipe will have a 25 U-shape lower end 19b terminating in a hollow plug 21a adapted to close the lower end of the tube 26a. Obviously, when coating material is passed through the pipe 19a it can be used to fill the tube to a desired height, and then the elevator will be 30 raised so that the coating material will flow out of the lower end of the tube.

In this form of the invention, overflow may be taken care of by an upstanding conduit 32a which 35 rises from the plug 21a. A passageway 33a in the plug provides for discharge from the overflow tube and a passageway 23a permits the material to flow from the pipe 19a into the tube.

This coating system is especially adapted for 40 coating with liquefied hot petrolatum which will protect the metal surfaces of the collapsible tubes and allow a small amount of coating material to remain in the threaded end of each tube coated. This is particularly important in connection with dual tubes as it effectually prevents the contents 45 of one tube coming in contact with the contents of the other tube prior to the same being expelled at the time of use.

Heretofore such tubes have been coated by 50 spraying a single tube at a time and the spraying process is only applicable to large tubes. Furthermore, the spraying process makes double spraying necessary as a single coat will not suffice. Moreover, as no lacquer has been satisfactory in spraying, such system has been abandoned as unsatisfactory.

There is another system known as the vertical lacquer gusher with high pressure. This coats only a single tube at a time and the tubes have to be turned about four times during drying to 55 avoid formation of a ring. As no lacquer or varnish in the vertical lacquer gusher system withstands alkali, this system is unsatisfactory.

In the first portion of this specification, I have 60 set forth the advantages of the invention over the known systems and while I have disclosed what I consider to be some preferred embodiments of the invention in such manner that the same may be readily understood by those skilled in the art, it is manifest that changes may be made in the 65 details disclosed without departing from the spirit of the invention as expressed in the claims.

What I claim and desire to secure by Letters Patent is:

1. An apparatus for coating collapsible tubes or 70 the like comprising a supply tank, means for feeding coating material from the supply tank and terminating in a plug, a tube support movable up and down relatively to said plug and adapted to support a collapsible tube with its spout end downwardly while the plug is closing the lower end of

the tube, and means for controlling the flow of the coating material through said means into the tube.

2. An apparatus for coating collapsible tubes or 75 the like comprising a supply tank, means for feeding coating material from the supply tank and terminating in a plug, a tube support movable up and down relatively to said plug and adapted to support a collapsible tube with its spout end downwardly while the plug is closing the lower end of 10 the tube, and means for controlling the flow of the coating material through said means into the tube, said plug having a conical face adapted to impinge against an annular internal surface of the tube.

3. An apparatus for coating collapsible tubes or 15 the like comprising a supply tank, means for feeding coating material from the supply tank and terminating in a plug, a tube support movable up and down relatively to said plug and adapted to 20 support a collapsible tube with its spout end downwardly while the plug is closing the lower end of the tube, means for controlling the flow of the coating material through said means into the tube, and means for preventing coating material rising in the tube beyond a predetermined 25 height.

4. An apparatus for coating collapsible tubes or 30 the like comprising a supply tank, means for feeding coating material from the supply tank and terminating in a plug, a tube support movable up and down relatively to said plug and adapted to support a collapsible tube with its spout end downwardly while the plug is closing the lower end of 35 the tube, means for controlling the flow of the coating material through said means into the tube, a sump to receive coating material discharged from the tube, and means for transferring coating material from the sump to the supply tank.

5. An apparatus for coating collapsible tubes or 40 the like comprising a supply tank, means for feeding coating material from the supply tank and terminating in a plug, a tube support movable up and down relatively to said plug and adapted to support a collapsible tube with its spout end downwardly while the plug is closing the lower end of 45 the tube, means for controlling the flow of the coating material through said means into the tube, a sump to receive material discharged from the tube, means including a 50 pump for forcing the coating material from the sump to the supply tank, and means for heating the sump, pump and supply tank.

6. An apparatus for coating the interior of 55 collapsible tubes or the like comprising a supply tank, means including a depending pipe for feeding coating material from the tank to a tube, a plug carried by the pipe, an elevator adapted to support a collapsible tube in inverted position while 60 the plug closes the lower end of the latter, means for placing the interior of the pipe in communication with the interior of the tube, and means for regulating the coating material fed through the pipe into the tube.

7. An apparatus for coating the interior of 65 collapsible tubes or the like comprising a supply tank, means including a depending pipe for feeding coating material from the tank to a tube, a plug carried by the pipe, an elevator adapted to 70 support a collapsible tube in inverted position while the plug closes the lower end of the latter, means for placing the interior of the pipe in communication with the interior of the tube, means for regulating the coating material fed through 75

the pipe into the tube, and an overflow conduit associated with the pipe and discharging through said plug.

8. An apparatus for coating the interior of collapsible tubes or the like comprising a supply tank for coating material, means for feeding the coating material from the tank into a collapsible tube, said means terminating in a hollow plug, an elevator adapted to support a collapsible tube in an inverted position, while the plug closes at the lower end of the tube and coating material is fed through the plug into the tube, and means for regulating the amount of coating material fed from the supply tank.

9. An apparatus for coating the interior of collapsible tubes or the like comprising a supply tank for coating material, means for feeding the coating material from the tank into a collapsible tube, said means terminating in a hollow plug, an elevator adapted to support a collapsible tube in inverted position while the plug closes the lower end of the tube and coating material is fed through the plug into the tube, means for regulating the amount of coating material fed through the plug, and means for preventing coating material rising in the tube beyond a predetermined height.

10. An apparatus for coating the interior of collapsible tubes or the like comprising a supply tank having a plurality of depending spouts, means for controlling the flow of coating material from the supply tank through the spouts, pipes associated with the spouts for feeding the coating material downwardly, plugs carried by the pipes, an elevator adapted to support a plurality of the collapsible tubes while such plugs close the spout ends of the tubes, means for feeding the material from the pipes into the tubes for filling the latter to a predetermined height, and a sump to receive coating material flowing from the tubes when the elevator is moved to unplug the tubes.

11. An apparatus for coating the interior of collapsible tubes or the like comprising a supply tank having a plurality of depending spouts, means for controlling the flow of coating material from the supply tank through the spouts, pipes associated with the spouts for feeding the

coating material downwardly, plugs carried by the pipes, an elevator adapted to support a plurality of the collapsible tubes while said plugs close the spout ends of the tubes, means for feeding the material from the pipes into the tubes for filling the latter to a predetermined height, a sump to receive coating material flowing from the tubes when the elevator is moved to unplug the tubes, and means for feeding the coating material from the sump to the supply tank.

12. An apparatus for coating the interior of collapsible tubes or the like comprising a supply tank having a plurality of depending spouts, means for controlling the flow of coating material from the supply tank through the spouts, pipes associated with the spouts for feeding the coating material downwardly, plugs carried by the pipes, an elevator adapted to support a plurality of the collapsible tubes while said plugs close the spout ends of the tubes, means for feeding the material from the pipes into the tubes for filling the latter to a predetermined height, a sump to receive coating material flowing from the tubes when the elevator is moved to unplug the tubes, means for feeding the coating material from the sump to the supply tank, a casing in which the supply tank, spouts, pipes, elevator, sump and last mentioned means are arranged, and means for heating the interior of the casing.

13. An apparatus for coating the interior of collapsible tubes or the like comprising a supply tank having a plurality of depending spouts, a device for controlling the flow of coating material from the supply tank through the spouts, means including pipes associated with the spouts for feeding the coating material, plugs carried by the pipes, elevator means adapted to support a plurality of collapsible tubes while said plugs close the spout ends of the tubes, passageways for feeding the coating material from the pipes into the tubes for filling the latter to a predetermined height, and a sump to receive coating material flowing from the tubes when one of said means is moved relatively to the other one of said means to unplug the tubes.

CLAUSS B. STRAUCH. 45
